The ornamental design of an adjustable chock for machinery, as shown and described.

DESCRIPTION

FIG. 1 is a front isometric view of an adjustable chock for machinery according to the present invention.

FIG. 2 is a front elevational view of the adjustable chock for machinery of FIG. 1, the rear, left side and right side elevational views being identical thereto.

FIG. 3 is a top plan view of the adjustable chock for machinery of FIG. 1; and,

FIG. 4 is a bottom plan view of the adjustable chock for machinery of FIG. 1.

The broken lines in the drawings are for the purpose of illustrating portions of the adjustable chock for machinery that form no part of the claimed design.
